(57) **CLAIM**

The ornamental design for a carbonated beverage carafe as shown and described.

DESCRIPTION

FIG. 1 is a top front perspective view of the carbonated beverage carafe, showing the design thereof.

FIG. 2 is a front elevational view thereof. The rear, left, and right views are mirror images thereof.

FIG. 3 is a top front perspective exploded view thereof.

FIG. 4 is a top rear perspective exploded view thereof.

FIG. 5 is a front exploded view thereof.

FIG. 6 is a rear exploded view thereof.

FIG. 7 is a right exploded view thereof.

FIG. 8 is a left exploded view thereof; and,

FIG. 9 is a top view thereof.

1 Claim, 6 Drawing Sheets
